COMBINATION AIR FILTER, INSECTICIDE, AND VAPORIZER ATTACHMENT FOR A VACUUM CLEANER

Vincenzo James Lee, Cleveland, Ohio

Application March 10, 1949, Serial No. 1,332

Term of patent 14 years

(Cl. D9—2)

To all whom it may concern:

Be it known that I, Vincenzo James Lee, a citizen of the United States, residing in the city of Cleveland, county of Cuyahoga, and State of Ohio, have invented a new, original, and ornamental Design for a Combination Air Filter, Insecticide, and Vaporizer Attachment for a Vacuum Cleaner, of which the following is a specification, reference being had to the accompanying drawing, forming a part thereof.

Figure 1 is a side elevational view of a combination air filter, insecticide, and vaporizer attachment for a vacuum cleaner, showing my new design;

Figure 2 is an end view thereof taken from the left of Figure 1;

Figure 3 is an end view thereof taken from the right of Figure 1; and

Figure 4 is a bottom plan view thereof.

I claim:

The ornamental design for a combination air filter, insecticide, and vaporizer attachment for a vacuum cleaner, substantially as shown.

VINCENZO JAMES LEE.
